SPINNERET FOR THE MANUFACTURE OF STAPLE FIBER FILAMENTS

Hermann Holzmann, Hanau on the Main, Germany, assignor to Deutsche Gold- und Silber-Scheideanstalt vormals Roessler, Frankfurt am Main, Germany, a corporation of Germany

Application December 6, 1949, Serial No. 131,331
In Germany December 3, 1948.

Public Law 619, August 23, 1954
Patent expires December 3, 1968

5 Claims. (Cl. 18—8)

This invention relates to spinnerets for the manufacture of staple fibre filaments, especially in the viscose process and pertains more particularly to an improved spinneret bottom with annular channels without spinning openings. The object of this invention is to provide a spinneret whereby at least one annular channel without spinning holes is arranged in addition to the radial hole-free channels.

A further object is to provide a spinneret with concentric annular channels whereby the intervals between the annular channels increase towards the center of the spinneret bottom. Other objects of my invention will be apparent as the detailed description of my invention proceeds.

The main disadvantage attendant upon the use of multi-perforated spinnerets for the manufacture of staple fibre filaments, especially according to the viscose process, was the difficulty in directing the precipitant bath fluid through the thick bundle of filaments to the holes at the center of the spinneret bottom. Furthermore, the precipitant bath becomes already partly neutralized or diluted inside the bundle of filaments and is therefore devoid of the same coagulating effect in the surrounding of the spinneret axis.

As it is known, this difficulty was soon overcome by arranging the openings in the spinneret bottom with interspaced channels for an easier inflow of the precipitant bath fluid towards the center of the spinneret instead of equally distributing the spinning holes over the whole spinneret bottom. Even in varying the shape and size of the channels, the latter are always arranged in radial direction.

I have discovered that the spinning capacity of multi-perforated spinnerets may be most favorably influenced, if, for instance, concentrically arranged annular channels are provided in addition to the radial channels. My invention relates therefore to a spinneret for the production of staple fibre filaments according to the viscose process, with radial hole recesses at the spinneret bottom whereby at least one annular channel exempt from openings is arranged in addition to the radial channels without spinning holes. These concentric annular channels connect the radial channels with each other, thereby causing a further guiding of the precipitant bath inflow which intensifies the distribution of the filament bundle.

Furthermore, this device also counteracts a too extensive deviation of the precipitant bath fluid in the direction of the filament bundle center. According to my invention the division of the spinneret bottom into radial and concentric recesses makes possible narrowing the intervals between the spinning holes in their respective bottom partitions to a higher degree than it was hitherto known. In my new spinneret the effect which is exerted by the particular subdivision of the spinneret bottom may be still further enhanced by arranging the concentric annular channel recesses containing the spinning openings in growing intervals, beginning at the periphery and leading to the center of the plate. A further advantage of my invention consists in the different width of the annular channels, whereby the width decreases from the periphery to the center of the spinneret bottom. Thereby the width may decrease from channel to channel either continuously or discontinuously, as, for instance, in pairs,

2

i. e. the two outer annular channels have the same width, whilst the centripetally adjusted third and fourth channels are narrower and so forth.

I have further found from experiments that spinnerets containing the new annular channels in addition to radial channels yield an excellent uniform quality of filament. These spinnerets are also more resistant against wearing away due to continued usage and superior to spinnerets with radial channels only. Moreover, the spinnerets according to my invention may contain a surprisingly large number of spinning holes in spite of recesses, due to the diminished intervals between the spinning holes without deteriorating the quality of the filament. Thus it is possible to obtain especially favorable conditions for the manufacture of staple fibre whilst observing the most economical use of the precious spinneret material. The new spinneret is therefore a distinct improvement in the production of rayon, especially staple fibre filaments.

I have illustrated a preferred form of my device in the accompanying drawings. Fig. 1 discloses the spinneret bottom in a plan view of the device. Fig. 2 discloses a segment of Fig. 1 in a larger scale.

In Fig. 1 I have shown four concentrically arranged annular channels exempt from holes (b_1, b_2, b_3, b_4) in addition to the usual radial channels without spinning holes, as indicated in Fig. 2, the intervals between the annular channels b_1, b_2, b_3 and b_4 (namely, the width of o_2, o_3 and o_4) increase from the periphery to the center of the spinneret plate bottom. Each pair of the annular channels has the same width. Thus, the width of the annular channels b_1 and b_2 corresponds to space d , whilst the width of the annular channels b_3 and b_4 is in accordance with the narrower space e . The series of the spinning holes are broader at the center of the spinneret bottom. Therefore the outermost row of holes shows the smallest width (o_1), the innermost row of holes the greatest width (o_3).

The channels may be carried out either in the form of planes without openings or in the form of grooves or notching. It is even possible to notch only one kind of the channels, i. e. either the radial or the annular channel whereby the grooved channels may die out into the plane ones.

What I claim is:

1. A spinneret for the production of staple fibre filaments having a plate provided with a plurality of spinning openings arranged about a center in groups spaced from each other to provide concentric annular opening free channels in said plate and to provide radial opening free channels in said plate extending towards said center between said groups of openings, said radial channels communicating with said concentric annular channels, the spacing between the groups of spinning openings providing the radial and annular opening-free channels being substantially greater than the spacing between the individual spinning openings in each group, and the openings in each group being arranged in a plurality of rows disposed at different distances from said center.

2. A spinneret for the production of staple fibre filaments having a plate provided with a plurality of spinning openings arranged about a center in arcuate groups spaced from each other to provide concentric annular opening free channels in said plate and to provide radial opening free channels in said plate extending toward said center between said arcuate groups of openings, said radial channels communicating with said concentric annular channels, the spacing between the groups of spinning openings providing the radial and annular opening-free channels being substantially greater than the spacing between the individual spinning openings in each group, and the openings in each group being arranged in a plurality of rows disposed at different distances from said center.

3. A spinneret for the production of staple fibre filaments having a plate provided with a plurality of spinning openings arranged about a center in arcuate groups spaced from each other to provide concentric annular opening free channels in said plate and to provide radial opening free channels in said plate extending toward said center between said arcuate groups of openings, said

radial channels communicating with said concentric annular channels, the spacing between the groups of spinning openings providing the radial and annular opening-free channels being substantially greater than the spacing between the individual spinning openings in each group, the openings in such groups being arranged in a plurality of rows disposed at different distances from said center have a greater width in the radial direction than arcuate groups further out from the center.

4. A spinneret in accordance with claim 3, in which the width of the annular opening free channels near the center is less than the width of the annular channels further out from said center.

5. A spinneret for the production of staple fibre filaments having a plate provided with a plurality of spinning openings arranged about a center in arcuate groups spaced from each other to provide concentric annular opening free channels in said plate and to provide radial opening free channels in said plate extending toward said center between said arcuate groups of openings, said
